INVENTOR,
Robert C. Piscator,
By *Joseph A. Minter*,
Attorney.

UNITED STATES PATENT OFFICE.

ROBERT C. PISCATOR, OF INDIANAPOLIS, INDIANA, ASSIGNOR TO QUALITY PLATING AND MANUFACTURING COMPANY, A CORPORATION OF INDIANA.

WINDOW STOP.

Application filed February 21, 1925. Serial No. 10,754.

My invention relates to means for holding a window in any position, and it is the primary purpose of my invention to provide such simple means as will automatically engage and hold windows, such as are commonly employed in closed automobiles, by direct contact of the window glass, and as may be released instantly without turning adjusting screws or unhooking elevating straps.

Further objects reside in the prevention of rattling of the windows, and the obtaining of a tighter grip or contact with the glass by vibration. A satisfactory window stop for the windows in an enclosed car has always been a problem, and the usual stop has heretofore consisted of a screw adapted to be turned up against the window, a strap attached to the bottom of the window and engaged over a stud or hook, or an elaborate crank device to raise or lower the window, none of which means has been of a durable nature nor permitted of any selective opening of the window other than at the predetermined points.

My invention eliminates the necessity of predetermining the window opening limits as above indicated, and is embodied in an article of manufacture adapted to be furnished as a replacement for the devices found on the windows. It may be made at an extremely low cost and the manufacturing process is exceedingly simple.

I accomplish these and such other objects as may be apparent in the following description by the means as shown in the accompanying drawing, in which—

Fig. 1 is a fragment of a wall in perspective showing my window stop holding a window in a partly raised position; Fig. 2, a side elevation of the stop; Fig. 3, a similar elevation of the stop, but with the retaining screw removed; Fig. 4, a horizontal section taken on the line 4—4 of Fig. 2; Fig. 5, an elevation of the glass contacting face of the stop cam; Fig. 6, a rear elevation of the stop with fragments of the cam and the window frame removed; Fig. 7, a side elevation of a modified cam; and Fig. 8, a side elevation of a still further modified cam.

Like characters of reference indicate like parts throughout the several views.

My stop is preferably adapted to contact the glass of a window rather than any frame that may contain the glass, although the stop

is operative in conjunction with such a frame.

I form a stop cam 10 of rubber with a face 11 adapted to contact the window glass 12. The cam 10 is cut through by a slot 13, Figs. 2 and 3, the slot 13 being formed at an angle with face 11 so as to recede backwardly away from the face 11.

A bushing 14, Figs. 3, 4, and 6, is loosely extended through the slot 13, and is provided with the stop shoulder 15. A back washer 16 is carried on the bushing 14 to contact the shoulder 15. An outer washer 17 confines the cam 10 on the bushing 14, by means of the screw 18 passing through the bushing and into the window frame 19 such that the head seats on the outer end of the bushing 14 and extends beyond the bushing sufficiently to act as an outer stop for the washer 17. By this structure, the cam 10 is free to travel on the bushing 14 throughout the length of the slot 13, such that by raising the cam 10, it travels away from the glass 12, by reason of the slot being inclined backwardly as in Fig. 3, where the cam 10 is shown by dash lines in its extreme upper position farthest removed from the glass 12, and by the solid lines in a lowered and forward position of contact with the glass. The relative position of the stop, the glass and the frame are best shown in Fig. 1, though the location of the stop may be varied at will so that where a replacement is made the old screw of a prior device may be removed to permit the substitution of the screw 18 of my stop. Where the frame is metal, a machine screw may be substituted for the wood screw as I have here shown.

In the face 11 of the cam which contacts the glass, I form a cup-like depression 20. By noting Figs. 2 and 3, particularly, it will be noted that the structure as I have above described shows a substantial wedge of the cam 10 lying between the screw 18 and the glass 12, such that by gravity alone, the cam 10 tends to remain in contact with the glass 12. Vibration, as is encountered in automobiles will tend to cause the cam to travel downward and therefore against the glass 12, such that the independent vibration of the glass 12 is stopped by the firm contact of the cam 10. A slight push downward on the cam 10 will accomplish the same result.

When the cam 10 is so positioned, it is

slightly compressed, depending upon the pressure by which it has been positioned, such that the air in the depression 20 has been partially pressed out, and any tendency to lift the cam 10, is resisted by the vacuum so formed. Furthermore, when the cam 10 is so pressed downwardly, it is pressed backwardly against the stop or screw 18, with the result that a substantial portion of the cam 10 is compressed to form the notch 21 behind the bushing 14, such that the shoulder on the notch 21 must be travelled over to permit raising the cam 10, thereby forming an additional locking means of holding the cam 10 firmly against the glass 12.

It is also apparent that any tendency of the window glass 12 to travel downwardly will serve to bring the cam 10 into firmer contact with the glass 12 by reason of the cam wedging between the stop screw 18 and the glass. The washers 16 and 17 serve as guides to direct the travel of the cam 10 and prevent any tendency of the cam 10 to buckle. By reversing the screw 18 and the bushing 14, the stop may be attached to either a right hand or left hand part of the window frame and no additional parts are required.

While the shape of the cam 10 as shown in Figs. 1-6, having a face 11 of considerable area contacting the glass, is a preferred form, the cam 10 may assume a variety of shapes as shown in Figs. 7 and 8. Fig. 7 shows a circular cam 22 with a straight slot 23 while Fig. 8 shows a circular cam 24 with an inwardly curving slot 25, both of which cam forms present a wedge adapted to be

squeezed against the glass between it and a screw or post.

I claim:

1. In a window stop, a rubber cam, a contacting face on the cam, said cam having a slot therethrough at an angle backwardly from the face, and a supporting post passing through the slot.

2. In a window stop, a yielding cam, a contacting face on the cam, said cam having a slot therethrough receding backwardly from the face, a supporting post passing through the slot, and said cam having a depression in said contacting face.

3. A window stop comprising a cam having a slot therethrough on an angle with the contacting face of the cam, and a post adapted to slide freely in said slot, said cam having an elastically yielding body about said slot whereby said post may be depressed in said cam body to act as a resistance to further travel of the post along said slot.

4. A window stop comprising a cam having a slot therethrough on an angle with the contacting face of the cam, and a post adapted to slide freely in said slot, said cam having an elastically yielding body about said slot whereby said post may be depressed in said cam body to act as a resistance to further travel of the post along said slot, and said cam having an elastically-yielding contacting face, said contacting face having a cupped depression.

Signed at Indianapolis, county of Marion, State of Indiana, this the 19th day of February, 1925.

ROBERT C. PISCATOR.
